UNITED STATES PATENT OFFICE.

JOSEPHINE L. HOLT, OF PORTLAND, OREGON.

CORSET.

1,322,018.

Specification of Letters Patent. Patented Nov. 18, 1919.

Application filed June 25, 1918. Serial No. 241,881.

To all whom it may concern:

Be it known that I, JOSEPHINE L. HOLT, a citizen of the United States, residing at Portland, in the county of Multnomah, and State of Oregon, have invented certain new and useful Improvements in Corsets, of which the following is a specification.

This invention relates to corsets, and more particularly to maternity corsets having a detachable abdominal supporter.

The object of the invention is to provide a simply constructed comfortable corset of this character adjustable, to suit the needs of the wearer, and which has an abdominal support transferable so as to be used in other makes of corsets when desired.

Another object is to provide an abdominal support which may be easily applied to any corset already in use, and may be quickly changed from one corset to another when the attachments for connecting it have been secured in the corset in connection with which it is to be used and which may be raised or lowered to suit the needs of the user.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:—

Figure 1 represents a perspective view taken from the inside of a corset constructed in accordance with this invention.

Fig. 2 is a detail horizontal section showing the connection of one end of the abdominal supporter to the corset.

Fig. 3 is a detail front view of a portion of the upper edge of the corset showing one means of securing the bones against punching through.

Fig. 4 is a longitudinal vertical section thereof.

Fig. 5 is a view similar to Fig. 3 showing another form of attachment to prevent the bone from punching through, and

Fig. 6 is a longitudinal section thereof.

In the embodiment illustrated, the corset 1 constituting this invention is composed of two members as is ordinary in corsets, with eyelets 1' along their rear edges to receive the lacing cords, and is equipped with supporters 2 for the hose, any desired number of which may be employed, three being here shown arranged at the front of each corset section. Each of these sections is slit inwardly from its lower edge as shown at 3, the side edges of the slit being reinforced as shown at 4 and elastic lacings 5 securing the edges of the slit adjustably together, so that while yieldable to provide for expansion, they may be also adjusted for this purpose.

Elastic strips 6 and 7 are secured to the upper edges of each corset section as is shown clearly in Fig. 1, the outer strip 7 being longer than the inner strip 6 and which render the corset expandable to fit the size of the wearer, and to hold it snugly against bulging at its upper edge.

Longitudinally disposed tapes 8 are arranged on the inner face of each corset section at the waistline as is usual in corsets, the front edges of said sections being closed by the usual hooks and eyes or any other suitable closing means.

A removable back section 9 is positioned between the rear ends of the two corset sections and secured in position by laces 10, which extend through eyelets 11 along the side edges of the back section 9 and through the eyelets 1' at the rear edges of the corset sections proper. This lacing connection of this removable back section provides for its adjustable connection with the corset section, and the back section itself is preferably constructed of elastic cloth or webbing, so that it will yield peripherally of the corset but not transversely.

The bones 12 of the corsets, any desired number of which may be employed, are inserted in the usual casings 13, stitched on the outer faces of the corset sections, and these bones have apertures 14 in their upper ends to receive connectors which pass through apertures in the casings 13 and in the body proper of the corset sections, and which are designed to receive any suitable means for securing these parts together.

As shown in Figs. 3 and 4, a piece of tape

or corset lacing 15 is passed through the registering eyelets in the bone, the casing and the corset, and have knots 16 formed on their outer faces to prevent disconnection, 5 and which will hold the bones against longitudinal movement upwardly. The casings 13 preferably have double rows of stitching arranged transversely thereacross at the lower ends of the bones 12 to prevent the 10 bones from working downwardly.

An abdominal supporter 20 is detachably mounted inside the corset, being constructed as shown in Fig. 1 to cup under and conform to the shape of a protruding abdomen, 15 being curved both longitudinally and preferably although not necessarily transversely, and composed of elastic webbing which is longitudinally yieldable and transversely non-yieldable. The supporter 20 proper is wider at the center than at its ends and is provided at said ends with adjustable connectors 21 and 21^a adapted for detachable connection with attaching elements 30 secured to the inner face of the 25 corset adjacent the under arm seams or just back of them, said elements 30 being in the form of strips stitched or otherwise secured to the corset and provided with eyelets 31 for a purpose to be described. The connectors 21 and 21^a each comprises a reinforcing strip 22 boned or otherwise as may be desired and provided with eyes 24^a along its front edge to detachably receive hooks 24 carried by a strip 23. The strip 23 has eyelets 25 along its rear edge to receive a lacing 28 which adjustably connects strip 23 with strip 26, which strip 26 has eyes 27 along its front edge to receive a lacing 28 which 30 detachably connects these two strips. Strip 26 also has another row of eyelets 29 spaced inwardly from these 27 and which are designed to form attaching means for connecting the strip 26 to the corset-carried strip 30. The belt attaching insert 30 is secured 35 one to each corset section, just back of the underarm seams, either by first slashing the corset at this point and then stitching the insert along the side edges as is shown clearly in Fig. 2, or it may be stitched 40 directly to the inner face of the corset without slashing or otherwise secured thereto. This insert 30 has a plurality of longitudinally extending eyelets 31 to receive a lacing cord 32 which also passes through 45 the eyelets 29 of strip 26 for detachably connecting said strip to the corset. While this connection for the strip 26 is here shown, obviously it need not be laced in, but may be stitched directly to the corset 50 if found desirable. By equipping several pairs of corsets with these attaching strips 30, one abdominal support 20 may be used in connection with all of them, as obviously said support may be quickly detached by

disengaging the hooks 24 of the attachment 65 from the eyes 22 of the supporter 20 or by unlacing cord 32.

By connecting the strips 23 and 26 with lacing cords 28 the supporter may be lengthened to conform to the increasing size of 70 the owner or to adapt the supporter to fit people of different sizes.

The supporter proper 20, as here shown, is reinforced and stiffened transversely by stiffeners 33, and loops 34 are provided at 75 its lower edge for attaching bandages or straps which may be found necessary for certain purposes.

Obviously, the supporter 20 may be supplied with its attaching means to any pur- 80 chaser, and used in connection with any form of corset by stitching the strips 26 to the corset sections just back of the under arm seams, or by slashing the corset and stitching in the inserts.

Owing to this fact, a manufacturer may carry a line of supporters totally independent of the corsets, but obviously the corset here shown, when used in connection with the supporter illustrated, will be a much 90 more valuable garment than an ordinary corset, particularly for maternity wear.

The foregoing description and the drawings have reference to what may be considered the preferred or approved form of my 95 invention. It is to be understood that I may make such changes in construction and arrangement and combination of parts, materials, dimensions, etc., as may prove expedient and fall within the scope of the 100 claimed invention.

Having thus fully described my invention, what I claim as new and desire to secure by Letters Patent, is:—

1. The combination with a corset having 105 inserts adjacent and just back of the underarm seams thereof and provided with longitudinally spaced eyelets, of an abdominal supporter, and attaching means for connecting the ends of said supporter with said inserts, each of said means comprising a strip or section having fastening elements at one side edge and eyelets at the other, a lacing cord adjustably connecting each section 110 with one insert, said supporter having co-operating fastening elements at its ends for detachable engagement with those at one edge of said attaching means.

2. An abdominal supporter comprising 115 a member shaped to cup under the abdomen, adjustable attaching members detachably engaged with said first-mentioned member, and means whereby said attaching members may be secured to a corset.

3. In a corset of the class described, two 125 sections having an expander interposed between the back edges of said sections, the lower front edges having inwardly extend-

ing slits reinforced along their edges and adjustably secured together, elastic strips secured one above the other to the upper edges of said sections and extending longitudinally thereof, and an abdominal supporter secured at its ends just back of the underarm seams of the corset sections, and means to permit the adjustment of said sup-

porter both vertically and horizontally relatively to the user. 10

In testimony whereof I affix my signature in presence of two witnesses.

JOSEPHINE L. HOLT.
